TAB

Nathan Bulwa, Bronx, and Emanuel Feibusch,
Brooklyn, N. Y.; said Feibusch assignor to said
Bulwa

Application May 16, 1934, Serial No. 725,882

4 Claims. (Cl. 206—82)

This invention refers to sample tabs of the kind used for displaying goods, for instance samples or pieces of fabric.

More particularly the invention relates to tabs 5 in which such samples may be readily mounted upon a suitable backing, for instance on a display card or in a sample book, so that the sample is spread, lies flat and/or shows to advantage.

The various objects of our invention are as 10 follows:—

1. To provide a tab in which a sample may be 15 readily and conveniently inserted, such tab being arranged in a simple fashion, so that it may be handled by any layman; at the same time it holds the goods properly and exposes it advantageously to the observer.

2. To provide for a tab which displays a maximum amount of the sample in a properly spread 20 fashion, and which also spreads, tightens and even slightly bulges the goods in order to provide a greatest possible effect upon the eye.

3. To provide means for properly engaging a sample, which facilitate the proper placing of the goods into the tab, and which assure that the 25 goods remain flat while the tab is being closed.

4. To provide for a tab in which the sample is engaged and mounted by a simple folding operation in one direction.

5. To provide for a tab in which, by way of a 30 simple folding operation, the goods are properly engaged and at the same time the tab, by folding, obtains the proper stiffness so that it offers a strong backing for the sample.

6. To provide for a display of the sample in 35 a plane, and for the display of the sample in the same width in full folds upon opposite sides so that a view of the sample is offered in which the light plays thereon at all angles.

7. To provide a simple folded tab in which a 40 sample is permanently and orderly mounted, and which retains the sample so that the tab may be opened, and which readily permits an opening of the tab and allows an inspection of the sample with light shining therethrough, and from both 45 sides.

8. To provide a simple tab, which may readily be opened for the purpose of touching, feeling and testing the goods, and in which the goods 50 are retained during such operations in orderly fashion so that the tab may readily be closed again for the ordinary display purposes.

9. To provide a tab, in which a plurality of samples may be assembled for the purpose of contrast and comparison. Provision is also made 55

that one sample may be mounted permanently in the tab, but others may be added at random or exchanged at will, without disturbing the first sample. At the same time the other samples will be held firmly and properly. 5

10. To provide a tab, simple in form and economical as to material and manufacture.

These and other objects of this invention will be more clearly understood from the following description and the accompanying drawing, in 10 which:—

Fig. 1 shows the back view of an unfolded blank.

Fig. 2 shows a tab from the back, in which one sample is mounted; another sample is being inserted for comparison. 15

Fig. 3 shows the face view of a sample tab with which a second sample is assembled for comparison.

Fig. 4 shows the face view of a sample tab as mounted on a backing. 20

Figs. 5, 6, 7, and 8 are back views of tabs with samples, illustrating the successive steps of closing up the tab.

While it is understood that the tab of this invention may be executed in various modifications, 25 we have adhered to one specific form of tab throughout the drawing, in order to facilitate a clear and unequivocal understanding of the principle of our invention.

The developed tab of Fig. 1 exemplarily forms 30 a rectangle comprising four sections, oblong plies 11, 12, 13 and 14, which may be a continuous sheet of flexible material, e. g. paper. The dot-dashed lines 15, 16 and 17 indicate scoring which facilitates the folding of the various plies upon 35 each other. From opposite sides of one of the plies, e. g. ply 13, extends flaps 18 and 19, as known in this art, one of said flaps, 18, being made longer, so that it may provide for a legend in the customary manner. One of the plies, e. g. 40 13, is provided with an opening 20, which serves as a window. This window may be given any desired shape. But we prefer to extend it into adjoining plies, e. g. 12 and 14, so that, in the case of the rectangular window shown, two corners 21 and 22 are in ply 12, and other two corners 45 23 and 24 are in ply 14.

The widths of plies 13, 12 and 11 are predeterminedly related to each other so that each one is of the same width as or a little wider than the 50 next one, and so that ply 11 may be folded onto plies 12; the folded together plies 11 and 12 fold onto plies 13, and plies 14 may be folded on top of the said folded plies. It is also an intent of this invention to have the folded-in plies fit snugly 55

within the folds of the other plies which are folded thereover.

Our tab may be used as follows:—A sample 25 is laid onto the back of the tab, as shown in Fig.

5 5, face down, so that the back 26 of the sample is exposed to view. Then the ply 11 is folded over, into the position shown in Fig. 6, so that the sample is now engaged between plies 11 and 12 and extends therefrom over the other plies.

10 Folding plies 11 and 12 over again, into the position of Fig. 7, the sample is wedged by the transverse free edge of tab 11 into the fold between plies 12 and 13 so that it is held squarely, and so that the sample is bulged and tightened

15 over the said edge and may possibly be seen from the back of the tab a small edge of the face 27 of the samples being thus exposed. In order to facilitate the understanding of the drawing, the back 26 of the sample 25 is hatched in spots, indicating woven threads, whereas a pattern of oblique stripes is shown on the face 27 of the sample 25.

20 As a last assembling operation, the ply 14 is folded over, pulling the sample tightly over the front of ply 11, the sample tab now having from the rear the appearance of Fig. 8. If it is turned over from that position so that it is seen from the front and is then mounted upon a sample card 28, by being inserted between two slits 29 and 30 thereof, the sample tab will offer from the front the appearance depicted in Fig. 4.

25 If we fold the sample back when the tab is in the position of Fig. 6, the sample tab will have the appearance shown in Fig. 2. We now may 35 deposit another sample on the ply 14, for instance a sample 31 in the folded position shown. If then the tab is folded over again, by straightening out the sample 25 and folding plies 11 and 12 onto ply 13, and plies 11, 12 and 13 onto ply 40 14, the tab offers the view of Fig. 3, with the sample 31 engaged therein.

30 We may fixedly mount the sample 25 between the plies 11 and 12; after they have been folded over onto each other for instance after they have 45 been folded over on each other in the position of Fig. 6, they may be stapled together by means of a clip 32. Or we may gum the free edge of ply 11 by an adhesive 33 so that the ply 11 will engage upon the sample when folded over and

the ends of ply 11 will permanently engage upon 5 ply 12. Or we may apply a dab of adhesive to the sample, as indicated at 34 in Fig. 5, either only a small amount, so that it adheres to ply 11 or 12 or a larger amount so that the adhesive 10 penetrates the sample and engages upon ply 12 as well as ply 11. When the sample is thus engaged upon the tab, it may be readily held up against the light, as in the modification of Fig. 6, and the observer may glance through the goods by way 15 of window 20 or the free end of the sample may be picked up and may be handled in the folded back position indicated in Fig. 2, so that the texture may be subjected to scrutiny by touch.

20 Although we have shown and described one 15 form of embodiment of our invention in detail, yet we do not wish to be limited thereby, except as the state of the art and the appended claims may require, for it is obvious that various modifications and changes may be made in the form 20 of embodiment of our invention, without departure from the spirit and scope thereof.

What we claim is:

1. In a sample tab, a plurality of connected plies, one of said plies being provided with a window, two other plies being disposed consecutively 25 on one side of said one ply and substantially registering therewith when folded thereonto.

2. In a tab for exhibiting a sample of ware, a plurality of connected plies, one of said plies 30 being provided with a window, two other plies being disposed consecutively on one side of said one ply, and an adhesive on one of the abutting faces of said two other plies. 35

3. In a sample tab, a plurality of connected plies, one of said plies being provided with a window, two other plies being disposed consecutively on one side of said one ply, and a sample engaged 40 upon one of the abutting faces of said two other plies.

4. In a sample tab, a plurality of connected plies, one of said plies being provided with a window, two other plies being disposed consecutively on one side of said one ply, a sample, and 45 means engaging one side of said sample between said two other plies.

NATHAN BULWA.
EMANUEL FEIBUSCH.
